RAILWAY TRAIN COMMUNICATION SYSTEM

Filed Dec. 12, 1944

UNITED STATES PATENT OFFICE

2,460,354

RAILWAY TRAIN COMMUNICATION SYSTEM

William L. Konrad, Pittsburgh, Paul N. Bossart, Cheswick, and Charles E. Leberknight, Emsworth, Pa., assignors to The Union Switch and Signal Company, Swissvale, Pa., a corporation of Pennsylvania

Application December 12, 1944, Serial No. 567,844

5 Claims. (Cl. 246—8)

1

Our invention relates to railway train communication systems.

Several methods of providing communication between spaced railway vehicles and between such vehicles and fixed points have been proposed. In train communication continuity of service at all points along the railway and under all weather conditions is essential. That is, communication must not be lost due to curves, cuts, tunnels, bridges and nearby factory buildings, or due to storms. Furthermore, a high signal to noise ratio is required because of the noise of a train in motion, and of the noise created due to stray magnetic fields, false currents and other electrostatic conditions. Also, the service should be confined to the railway right-of-way, so that there is privacy in the communication. Again, systems using apparatus requiring no government license or assignment of wave bands are desirable.

In view of the foregoing circumstances, a feature of our invention is the provision of improved railway train communication apparatus.

Another feature of our invention is the provision of improved railway train communication apparatus for utilizing the track rails and existing line wires and other conductors paralleling the track as a channel through which communication current is transmitted and guided along the railway.

Still another feature of our invention is the provision of improved railway train communication apparatus to minimize noise.

Again, a feature of our invention is the provision of improved railway train communication apparatus which substantially confines its influence to the railway right-of-way, and which apparatus requires no wave band license.

Other features, objects and advantages embodying our invention will appear as the specification progresses.

The general features of our invention are obtained through the provision of train carried elements disposed for the transfer of electrical energy between such elements and the track rails and other conductors paralleling the track. The current used is such that the rails and paralleling conductors through their distributed impedance to ground and distributed inductance-capacitance, serve as a channel through which the cur-

2

rent is guided along the trackway, the channel being made up of a plurality of paths each of which adds something to the sum total of the transmission. At some points along the railway, the track rails may be the more effective portion of the channel, and at other points the existing paralleling line wires and other conductors may be the more effective portion of the channel. Furthermore, the current used is such that it is largely confined to this channel and its influence extends only for short distances at right angles to the track. To minimize the noise we provide transmitting and receiving apparatus which utilizes frequency modulation, the frequency of the carrier being preselected to be substantially free from interference with other systems and to be suitable to effect transmission and reception with a relatively low energy output.

We shall describe one form of apparatus embodying our invention, and shall then point out the novel features thereof in claims.

The accompanying drawing is a diagrammatic view showing one form of railway train communication apparatus embodying our invention.

Referring to the drawing, the reference character CO represents a railway train vehicle on which two-way communication apparatus embodying our invention is installed. This vehicle CO may be, for example, a caboose of a freight train, and the apparatus installed thereon includes transmitting apparatus and receiving apparatus which are indicated as a whole by the reference characters TA and RA, respectively.

The caboose CO is provided with a source of power which is shown as a motor generator MG, the motor 7 of which is supplied with current by any suitable means, such as an axle driven generator and storage battery of the common 32 volt car lighting system, the terminals of such

current source being indicated in the drawing as B32 and N32. Generator 8 of the motor generator MG supplies power at a voltage suitable for use with vacuum tubes of the transmitting and receiving apparatus to be described shortly.

The positive and negative terminals of the generator G are indicated in the drawing as B300 and N300, respectively, the terminal N300 being connected to a ground electrode 9 which may be the metal frame of the caboose.

The caboose CO has mounted thereon sending

and receiving elements through which energy is transferred between the train carried apparatus and the trackway communication channel. The sending element to transfer energy between the transmitting apparatus TA and the trackway channel comprises a loop circuit LC and a coil SC. The loop circuit LC includes a wire 2 connected to a pair of wheels 4 at one end of the caboose, condenser C1, and wire 3 connected to a pair of wheels 5 at the other end of the caboose. The circuit LC is completed between these two pairs of wheels through the track rails. In the drawing only one rail of the track and only one wheel of each of the pairs of wheels are shown for the sake of simplicity. To confine such loop circuit, the two pairs of wheels 4 and 5 are preferably insulated from the body of the caboose. Such insulation may be of different constructions and is indicated conventionally by insulation IN between each truck and the caboose body. This insulation may be, for example, insulation placed at the journal bearings in the manner covered by Letters Patent of the United States No. 2,064,642, granted December 15, 1936 to Paul N. Bossart for Railway train communication systems. The connection of wires 2 and 3 to the respective pair of wheel may be through terminals secured to the ends of the journal bearing brasses as disclosed in the above-mentioned Bossart patent, there being preferably a connection to the journal bearing brass of each wheel of each pair of wheels to insure a balanced condition. It is to be noted, however, that this insulation may be effected by insulating one truck or one pair of wheels and insulating the front draw bar of the caboose, the draw bar insulation being provided to avoid a shunting of the current through the cars of a train to which the caboose is attached.

The sending coil SC is preferably a rectangular shaped air core coil suspended from the floor of the caboose. In practicing the invention the coil SC would preferably be made up of two coils, one over each rail, and the two coils connected together to add their effects.

It is clear that the loop circuit LC is a coil of one turn having inductive relationship with coil SC and that periodic current supplied to coil SC induces a corresponding electromotive force in the loop circuit causing current to flow therein and thus create a corresponding voltage drop across the rails between the spaced pairs of wheels 4 and 5. The capacitance C1 tunes the loop circuit to the frequency band of the communication current to increase the flow of current. The major portion of the impedance of this loop circuit is the impedance of the rails and thus the voltage drop across the rails represents the major portion of the power consumed. The voltage drop across this length of the rails causes current to flow through the rails in multiple to each side of the caboose and through the distributed rail to ground impedance, the current being of a relatively large magnitude near the caboose and attenuated to a relatively low magnitude at points remote from the vehicle. The relatively large current flowing in the rails near the vehicle induces an electromotive force in existing line wires, such as line wire LW, and other parallel conductors due to the mutual inductance between the rails, circuits SC and LC and such conductors. The line wire electromotive force in turn causes current to flow in such line wires due to the distributed capacitance of the line wires to ground, and at point remote from the vehicle the current flowing in the line wires

is relatively large compared to that remaining in the rails with the result that the current in the line wires induces electromotive forces in the rails due to the mutual inductance between the line wires and the rails. This last mentioned electromotive force in turn causes current to then flow in the rails due to the distributed rail to ground impedance. That is to say, the trackway channel includes the rails, existing line wires and other conductors paralleling the tracks, and such channel serves to transmit and guide the communication current along the right of way. This transmission of current is explained more fully in the aforementioned Bossart patent and reference is made thereto for a full understanding of the transmission of communication current along such a trackway channel.

The receiving element of caboose CO for picking up energy from the trackway channel is an air core coil RC mounted in a vertical plane on the top of the caboose. In this position the coil RC is disposed to pick up an electromotive force when a periodic current flows in the trackway channel.

The transmitting apparatus TA, the output of which is connected to the sending coil SC, comprises as essential elements a microphone M1, a frequency modulating means, and one or more stages of amplification. The modulation means comprises a tube V1 and an oscillator tube V2, together with the necessary circuits and sources of power. The amplifying means comprises two stages of amplification, including tubes V3 and V4 although it is clear that the number of stages may be more or less than those shown. The several vacuum tubes of the transmitting apparatus may be of any suitable type and indirectly heated pentodes are shown, the filament of each tube being heated in any convenient manner.

Tube V1 is provided with a control grid circuit, including control grid 10, reactance coil 11, secondary winding 12 of a transformer T1, biasing unit BU1 and cathode 13; and with an anode circuit extending from terminal B300 of the source of power through front contact 19 of a relay DR1, to be referred to later, wire 20, resistor 132, reactance coil 21, anode 22 and tube space to cathode 13 of tube V1, unit BU1, and ground electrodes 18 and 9 to terminal N300 of the source of power. Primary winding 14 of the transformer T1 is interposed in a microphone circuit comprising microphone M1, battery 15, primary winding 14, ground electrodes 18 and 9, front contact 17 of relay DR1, and wire 16. It follows that voice frequencies created in the microphone M1 are applied to the control grid 10 of tube V1 through the transformer T1 and corresponding variations in the anode current are produced. A gas tube V8 of the cold cathode type is preferably connected to the anode circuit and serves as a voltage regulator.

Oscillator tube V2 has associated therewith an oscillating circuit comprising an inductance coil 23, two capacitors 24 and 25 and resistor 26. Capacitor 24 in series with resistor 26 and the combination in multiple with capacitor 25 are connected across the coil 23. One terminal of this oscillating circuit is connected to control grid 27 of tube V2 through a unit BU2 and its other terminal is connected to ground electrode 31. An intermediate terminal of coil 23 of the oscillating circuit is connected to cathode 28 of tube V2 to form with the first two grids of tube V2 the well-known Hartley oscillator circuit. An anode voltage supply circuit for tube V2 which

functions as an electron coupled oscillator is formed from terminal B300 of the power source through front contact 19 of relay DR1, wire 20, resistor 29, anode 30 and tube space to cathode 28, intermediate terminal and lower portion of inductance coil 23 and ground electrodes 31 and 9 to terminal N300. Coil 23 and capacitor 25 are so proportioned that the oscillations generated by the cathode and the first two grids of tube V2 are of a preselected carrier frequency, and by way of illustration and to aid in an understanding of our invention, we shall assume that a carrier of 88 kilocycles per second is generated. It is to be understood that our invention is not limited to this carrier frequency and other frequencies can be used. However, the carrier frequency is preferably preselected to provide efficient transfer of energy through metallic conductors and by induction.

The tube V1 is coupled to the oscillating circuit through capacitors C2 and C3 and consequently voice frequency current applied to tube V1 causes this tube to appear as a changing capacity across capacitor 25 of the oscillating circuit and the frequency created thereby is varied. That is to say, the tube V1 serves as a variable reactance through which the carrier is frequency modulated in accordance with the voice frequencies.

Amplifier tube V3 is provided with a control grid circuit comprising control grid 32, resistor 33, biasing unit BU3 and cathode 34; and with an anode circuit extending from terminal B300 through front contact 19 of relay DR1, wire 20, primary winding 35 of a transformer T2, anode 36 and tube space to cathode 34, unit BU3 and ground electrodes 31 and 9 to terminal N300. The control grid circuit of tube V3 is coupled to the anode circuit of the oscillator tube V2 through a capacitance C4, and consequently the output of the oscillating circuit is amplified at tube V3, the amplified output of tube V3 being a frequency modulated carrier telephone current.

Amplifier tube V4 is provided with a control grid circuit including control grid 37, secondary winding 38 of transformer T2, resistor 39, biasing unit BU4 and cathode 40; and with an anode circuit receiving current from terminal B300 through front contact 19 of relay DR1, wire 20, winding 41, anode 42 and tube space to cathode 40, unit BU4 and ground electrodes 43 and 9 to terminal N300. It follows that the amplified frequency modulated telephone current is further amplified at tube V4.

The anode circuit of tube V4 is coupled to the sending coil SC through a capacitance 45, winding 44 and capacitance 108 in multiple and ground electrode 98. Thus the frequency modulated carrier telephone current as amplified by tube V4 is supplied to the sending coil SC to be transferred to the trackway channel in the manner already explained.

The receiving apparatus RA includes as essential elements an amplifier AM1, a limiter including a vacuum tube V5, a discriminator including a vacuum tube V6, and two audio amplifying stages including tubes V7 and V8.

Amplifier AM1 may be any one of several standard forms of amplification, and may include one or more stages as desired; and this amplifier is shown in block form for the sake of simplicity.

The pick-up coil RC is connected to the input side of the amplifier AM1 by coil RC being connected to primary winding 91 of a transformer T3, a secondary winding 92 of which transformer

is connected to the amplifier in series with a capacitance 93, another capacitor 94 being connected across the secondary winding 92. Resistor 95 is connected across the input of amplifier AM1. The output side of amplifier AM1 is coupled to the control grid 46 and cathode 47 of limiter tube V5 through a transformer T4, as will be readily understood by an inspection of the drawing. Tube V5 is shown as an indirectly heated pentode having an anode circuit supplied with current from terminal B300 through back contact 48 of relay DR1, reactance coil 49, wire 50, resistors 51 and 52, winding 53 of a coupling transformer T5, anode 54 and tube space to cathode 47 and ground electrodes 55 and 9 to terminal N300. The parts are so proportioned that tube V5 is provided with a relatively low anode voltage and functions to limit the amplification of the oscillations applied to the control grid of the tube through the amplifier AM1. Thus the oscillations picked up by the receiving coil RC are reproduced in the output of the limiter tube V5 at substantially uniform amplitude.

The anode circuit of tube V5 includes a tuned circuit comprising capacitor C7, resistor 78 and winding 53 of transformer T5, and this tuned circuit is coupled to another tuned circuit including capacitor C8, resistor 65 and winding 56 of transformer T5. These two circuits are tuned to resonance at substantially the carrier frequency. The outside terminals of the tuned circuit including winding 56 are connected to the anodes 57 and 58 of discriminator tube V6, tube V6 being a diode type of tube. Mid terminal of secondary winding 56 is connected through an inductance coil 61 to the junction terminal of resistors 62 and 63, the outside terminals of which resistors are connected to the cathodes 59 and 60, respectively, of the two sections of tube V6. Consequently, a resultant direct voltage varying in amplitude according to the frequency variation of the energy applied to the tuned circuits appears across the resistors 62 and 63.

Amplifier tube V7 is a triode having a control grid circuit including resistor 64 and a biasing unit BU5, and which grid circuit is coupled to resistors 62 and 63 of the discriminator through a capacitor C5. Thus the direct voltage variations appearing across the resistors 62 and 63 are applied to the control grid circuit of tube V7 and cause corresponding variations in the amplitude of the anode circuit current of this tube, and which anode circuit receives power from terminal B300 through back contact 48 of relay DR1, coil 49, wire 50, resistor 66, anode 67 and tube space to cathode 68, unit BU5, and ground electrodes 55 and 9 to terminal N300.

The second stage amplifier tube V8 is of the pentode type, and its control grid 69 is coupled to the anode circuit of tube V7 through capacitor C6, and the anode current variations of tube V7 are further amplified by the tube V8 in the usual manner. A coupling transformer T6 has a primary winding 70 interposed in the anode circuit of tube V8 and a secondary winding 71 included in a circuit for a loud speaker LS, this loud speaker circuit being completed through back contact 72 of relay DR1 and ground electrodes 9 and 73.

Normally, that is, with relay DR1 released, power is applied to the anode circuits of the tubes of the receiving apparatus RA and the loud speaker circuit is closed so that the receiving apparatus is normally active, but the transmitting apparatus TA is inactive due to the anode cir-

cuits of its various tubes being deenergized and the microphone circuit being open. In describing the operation of the system of the apparatus, it is to be understood, of course, that apparatus similar to that provided for caboose CO is mounted on another vehicle of the train or at some wayside station and that communication is effected between these two points through the medium of the trackway channel.

If a communication current consisting of a pre-selected carrier frequency modulated by the voice frequency is picked up by coil RC at caboose CO, such current is amplified at the amplifier AM1, any variation in the amplitude of the current is limited at the limiter tube V5, the frequency variations of the current are reproduced as variations in amplitude of a direct voltage by the discriminator and such direct voltage variations are amplified at tubes V7 and V8, and the voice frequencies which the direct voltage variations represent are reproduced at the loud speaker LS. If the trainman in the caboose wishes to reply to such received speech or if he wishes to initiate a conversation, he depresses a push button PB to complete a simple circuit for energizing relay DR1 and that relay on picking up switches the power source from the anode circuits of the receiving tubes to the anode circuits of the transmitting tubes, and serves to energize the microphone circuit. Speaking into the microphone M1 causes corresponding variations in the frequency of the carrier supplied through the oscillator tube and such frequency modulated carrier after further amplification is applied to the communication channel of the trackway to effect the receiving apparatus at the remote office. From this point on, proper operation of the push button PB to switch from sending to receiving conditions permits the caboose to carry on a conversation with the remote station.

Train communication apparatus here disclosed has the advantages that the communication current is transmitted and guided along the track and loss of communication due to curves, cuts and other conditions is avoided. Secrecy of communication is obtained because of the confining of the communication current to substantially the right of way. Noise is minimized because of the modulation used and arrangement of apparatus. Furthermore, relatively simple and inexpensive apparatus is required.

Although we have herein shown and described only one form of railway train communication systems embodying our invention, it is understood that various changes and modifications may be made therein within the scope of the appended claims without departing from the spirit and scope of our invention.

Having thus described our invention, what we claim is:

1. In combination, a railway train vehicle having mounted thereon transmitting apparatus operable to supply a periodic current of a given frequency, a closed single turn secondary circuit on said vehicle connected to spaced pairs of wheels of the vehicle to include a portion of the track rails in the circuit and completed through capacitance to tune the circuit to the frequency of said periodic current, said secondary circuit being characterized by the impedance of the rails being a major part of the circuit impedance, and a primary circuit on the vehicle including an air core coil mounted within said secondary circuit for mutual inductance with said secondary circuit and

connected to said transmitting apparatus to cause such periodic current to flow in the rails.

2. In combination, a railway train vehicle having mounted thereon transmitting apparatus operable to supply a periodic current of a preselected frequency band, a closed secondary circuit including a conductor extending lengthwise of the vehicle and each end of which conductor is connected to a pair of wheels at the respective end of the vehicle to include a given length of the track rails in the circuit, a capacitor included in series with said conductor to tune the secondary circuit to resonance at the mean frequency of said frequency band, a primary circuit including an air core coil mounted within said secondary circuit for mutual inductance to both the rails and said conductor of the secondary circuit, and said primary circuit connected to said transmitting apparatus to transfer said periodic current due to the mutual inductance of said coil with said conductor and track rails.

3. In combination, a railway train vehicle having mounted thereon transmitting apparatus operable to supply a given periodic current, a closed secondary circuit including a low impedance conductor extending lengthwise of the vehicle through a capacitor and having each end connected to a pair of wheels at the respective end of the vehicle to include a portion of the track rails in the circuit, said secondary circuit characterized by one side being formed solely by said conductor and capacitor for the rails in the other side of the circuit to form the major portion of the impedance of the circuit and the voltage drop across such portion of the rails is a large percentage of the total voltage drop of the circuit when periodic current flows therein, a primary circuit including a large air core coil mounted on the vehicle for mutual inductance with said secondary circuit, and said primary circuit connected to said transmitting apparatus for transfer of said periodic current to the track rails through said secondary circuit.

4. In combination, a railway track along which a line wire extends, the rails of said track and said line wire forming a transmitting channel for periodic current due to their distributed mutual inductance and distributed impedance to ground, a railway train vehicle having mounted thereon transmitting apparatus capable of supplying periodic current of a preselected frequency band, an air core coil connected to said transmitting apparatus, a single turn sending loop circuit having one side formed by a conductor extending lengthwise of the vehicle between two spaced pairs of wheels of the vehicle and the other side formed by the rails in multiple between said two pairs of wheels, a capacitor interposed in said conductor to tune the sending circuit for said frequency band, and said air core coil mounted on the vehicle within the sending circuit for mutual inductance with the sending circuit and said line wire for transfer of the periodic current of the transmitting apparatus to said transmitting channel.

5. In combination, a railway track along which a line wire extends, the rails of said track and said line wire forming a transmitting channel for periodic current due to their distributed mutual inductance and distributed impedance to ground, a railway train vehicle having mounted thereon transmitting apparatus capable of supplying periodic current of a given frequency band, an air core coil connected to said transmitting appa-

status, a single turn sending loop circuit including the track rails in multiple between two spaced pairs of wheels of the vehicle and a conductor extending lengthwise of the vehicle between said two pairs of wheels, and said air core coil mounted on the vehicle between said conductor and the track rails for inductive relation to the conductor and rails of said sending loop circuit and to the line wire for transfer of said periodic current from the transmitting apparatus to said transmitting channel.
